Patented Dec. 2, 1958

183,999

PORTABLE RADIO CABINET

Melvin H. Boldt, Glenview, Ill., assignor to Zenith Radio
Corporation, a corporation of Delaware

Application January 24, 1958, Serial No. 49,389

Term of patent 14 years

(Cl. D56—4)

FIG. 1

Figure 1 is a front perspective view of a portable radio cabinet, showing my new design with the front panels in an open position;

Figure 2 is a perspective view similar to Figure 1 except showing the front panels in a closed position; and

Figure 3 is a side elevational view of the cabinet with the front panels open.

The dominant features of my design reside in those portions shown by means of full lines in the drawing. The back of the cabinet is substantially plain and without essential ornamentation.

I claim:

The ornamental design for a portable radio cabinet, substantially as shown and described.
